UNITED STATES PATENT OFFICE.

JOHN A. RENNIE, OF LYNDHURST, NEW JERSEY, ASSIGNOR TO UNDERWOOD TYPE-WRITER COMPANY, OF NEW YORK, N. Y., A CORPORATION OF DELAWARE.

TYPE-WRITING MACHINE.

1,152,972.

Specification of Letters Patent.

Patented Sept. 7, 1915.

Application filed December 3, 1910. Serial No. 595,333.

To all whom it may concern:

Be it known that I, JOHN A. RENNIE, a citizen of the United States, residing in Lyndhurst, in the county of Bergen and 5 State of New Jersey, have invented certain new and useful Improvements in Type-Writing Machines, of which the following is a specification.

This invention relates to means for feeding envelopes to the platens of typewriting machines.

It has been usual to pack the envelopes in a receptacle which has been mounted upon the letter-feeding carriage of the writing machine; and the weight of the envelopes as 15 well as the weight of the receptacle itself, has proved a serious objection, because the weight of the carriage is so increased thereby that promptness in its letter-feeding action has been sacrificed.

One of the main objects of the present invention is to overcome this difficulty, and to that end I have contrived to relieve the carriage altogether of the weight of the pack- 25 age of envelopes and the envelop receptacle. This receptacle with its envelopes I mount upon, or connect to, the stationary machine frame; and the carriage is thus not burdened with its weight, nor is the letter-feeding 30 movement of the carriage retarded, by reason of the necessity of putting the extra mass into action at each letter-feeding operation.

In directing an envelop, it is customary 35 to indent all lines after the first line of the address. Hence the paper carriage is moved back farther for beginning the first line of writing, than it is for beginning the succeeding lines. I have contrived a mech- 40 anism whereby when the paper carriage is moved back far enough to begin the first line of the address, an envelop is automatically picked up from the pile or stack and fed into the machine. Hence the machine 45 receives a new envelop as often as it is necessary to begin the writing of a first line. Therefore, the operator needs to pay no attention to the feeding of the envelopes; suitable means being provided for carrying 50 them through the machine in the required manner.

Since the envelopes and the receptacle are not carried upon the paper carriage, their weight is not limited, and hence it is practi-

cable to place very many envelops in the 55 receptacle, instead of the limited number which has heretofore been usual.

Other objects and advantages will herein-after appear.

In the accompanying drawings, Figure 1 60 is a front view of one form of the invention applied to the platen frame of an Underwood writing machine, the parts being in idle position. Fig. 2 shows the envelop inserted between the auxiliary feed rolls and 65 the platen, ready to be fed to position to have the first line printed thereon. Fig. 3 is a side view, of the device partly broken away, the typewriting machine being shown in section. Fig. 4 is a detail plan of one 70 end of the platen frame, showing the control of the auxiliary feed rolls by the line-space mechanism.

Types 1 strike against a platen 2 fixed to an axle 3 journaled in the ends 4 of a platen 75 frame 5, mounted on a carriage 6. Said carriage and platen are movable endwise in letter-spacing direction and along a rail 7 secured to the main frame 8. The platen has the usual rear and front feed rolls 9 and 80 9^a, and may be rotated either by turning the usual finger wheels 10 fast on the axle 3 or by a line-space lever 11 which operates a slide 12 having a pawl 13 to engage a line-space wheel 14 fast on the axle 3. Pressure 85 against the lever 11 turns the platen through one or more line spaces and returns the carriage 6 toward initial position.

An envelop receptacle comprising sides 15 and a bottom 16, is mounted upon a 90 bracket 17 which may be secured to the frame 8 of the machine; whereby the carriage is relieved of the weight of the receptacle and its contents. This arrangement enables the receptacle to be made large 95 enough to hold any desired number of envelops 18, which are placed between the sides 15 in inverted position with their flaps 19 to the front. The delivery end of the receptacle overhangs the platen frame, and 100 a guard 20 partially closes said end to hold the stack of envelops against falling out.

The bottom 16 of the receptacle is cut away at its forward end to form an opening 24 through which the envelops are thrust. 105 A weight or follower 21, which in the present instance, has rolls 22 running upon the forwardly and downwardly inclined bot-

tom 16 of the receptacle, feeds the stack of envelopes toward the delivery end.

The mechanism for extracting the envelopes singly from the receptacle and supplying them to the carriage, is controlled by the carriage on its return movement to begin the first line of a new address.

As the carriage approaches initial position (Fig. 1) the left-hand end 4 of the 10 platen frame strikes a tappet on the free end of a feed lever 25 pivoted at 26 preferably to an ear 27 on the envelop receptacle. The feed lever or arm 25 communicates motion to a short arm 28 having a pin and slot 15 connection 29, 30 with the feed lever.

The arm 28 is fast on a shaft 31, journaled in ears 32 on the receptacle. The comparatively slight rotation of the shaft 31 swings downwardly a motion-multiplying arm 33 secured to the shaft, and having a link 34, connecting it with a vibratory frame, which comprises a cross bar 35, vibrating in front of the guard 20. Said frame has slides 36 at its opposite ends 25 mounted on upstanding guides 37, at opposite sides of the delivery end of the receptacle. Ejectors 38 depend from the frame 35, and a downward movement of the frame inserts the lower ends of said ejectors under 30 the flap 19 of the foremost inverted envelop 18 (which for this purpose is caused to protrude through an opening 23 between the guard 20 and the bottom 16 of the receptacle by the pressure of the follower 21 against 35 the rear end of the stack of envelopes), to thrust said envelop through the discharge opening 24. By the time the carriage reaches initial position, the envelop has been thrust downwardly behind the platen, (Fig. 40 2), the frame 35 being arrested by the contact of the slides 36 with stops 39 on the guides 37.

An auxiliary feed roll mechanism may be provided to assure the advance of the envelop to the usual feed rolls 9. Auxiliary feed rolls 40 engage the rear face of the platen 2, such rolls being journaled on a shaft 41 fast in arms 42 of a frame 43 pivoted on the usual tie rod 44 connecting the 50 platen frame ends 4.

Returning the carriage toward initial position by pressing the line space lever 11 forces the slide 12 rearwardly. A lip 45 on the slide (Fig. 4) then strikes a link 46 pivoted by a slot 47 and pin 48 (Fig. 3) to the inner face of the left hand platen frame end 4, the rear end of the link being hinged to the outer end of the shaft 41, to swing the frame 43 and cast off the auxiliary feed rolls 60 40. The shaft 41 is fixed against turning in the arms 42, as by having one end squared and fitted in a corresponding aperture in one of said arms as at 55 (Fig. 1). The rolls are released prior to the operation of 65 the ejecting mechanism and lie out of the

path of the leading edge of the envelop 18 which is advanced by the ejectors 38 to a plane below the rolls 40.

The spacing lever 11 is released the moment the carriage reaches its initial position (Fig. 2), whereupon the slide 12 is returned to normal position by the usual spring 49, and a returning spring 50 causes the auxiliary feed rolls 40 to press the envelop 18 against the platen. By turning the finger 75 wheels 10, the platen is rotated to advance the leading edge of the envelop downwardly to the bite of the rear feed rolls 9 and platen after which a continued turning of the platen feeds the envelop in the usual manner. 80

The first line of the address is now written, the carriage being fed in letter-spacing direction, at each type stroke, thereby enabling a returning spring 51 to raise the ejecting frame 35 and swing the feed lever 85 25 back to normal position (Fig. 1). Stops 53 arrest the frame 35 in normal position. The first line having been written, pressure against the lever 11 advances the envelop and returns the carriage to position to commence the second line of the address. Said second line, however, is begun with the carriage a short distance to the left of its initial position so that the ejecting mechanism is not actuated at this time. The auxiliary 90 feed rolls 40 may, in some cases, be omitted.

Though my invention has been illustrated and described in detail as it is adapted to be used in feeding envelopes, it is obvious that various portions of it may be used in feeding devices for cards, sheets and other work pieces. So the word "envelop" which is used for convenience and brevity throughout the specification, is to be understood in every instance as covering such cards, sheets 105 and other work pieces as far as the structure of the parts then under consideration is applicable to handling such cards, etc.

Variations may be resorted to within the scope of the invention, and portions of the 110 improvements may be used without others.

Having thus described my invention, I claim:

1. The combination with a writing machine including a paper carriage to travel in letter spacing direction and return, a platen mounted in the carriage, and feed rolls on the platen, of a work piece receptacle, mechanism dependent upon the return of the carriage toward initial position to automatically feed the work pieces singly, and an auxiliary feed roll on the carriage to which the work pieces are delivered from the receptacle. 115

2. The combination with a writing machine including a carriage fed in letter spacing direction, a platen mounted on the carriage, and feed rolls co-acting therewith, of a stationary work piece receptacle, mechanism operable by the carriage on its return 120 130

5 toward initial position to feed work pieces singly from the receptacle, and an auxiliary feed roll operating subsequently to the first-named feed mechanism to advance the work-pieces to the feed rolls.

10 3. The combination with a writing machine including a carriage fed in letter-spacing direction, a platen mounted thereon, and feed rolls on the platen, of a work piece receptacle, a vibratory frame, ejectors on the frame, mechanism operated by the carriage on its return toward initial position to vibrate the frame, and an auxiliary feed roll to which the ejectors deliver the work piece.

15 4. The combination with a writing machine including a carriage fed in letter-spacing direction, a platen mounted to rotate thereon, line-spacing mechanism controlling the rotation of the platen, and feed 20 rolls for the platen, of a work piece receptacle, work piece feeding mechanism therefor, and an auxiliary feed device controlled by the line-space mechanism to which the work-pieces are delivered, and by which they 25 are introduced between the platen and feed rolls.

5. The combination with a writing machine including a carriage fed in letter-spacing direction, a platen mounted to rotate 30 thereon, line-spacing mechanism controlling the rotation of the platen, and feed rolls for the platen, of a work piece receptacle, work piece feeding mechanism therefor, and a swinging feed roll controlled by the line-space mechanism to engage the work piece and advance it to the main feed rolls after it has been delivered to the platen.

40 6. The combination with a writing machine including a carriage fed in letter-spacing direction, a platen mounted to rotate thereon, line-spacing mechanism controlling the rotation of the platen, and feed rolls for the platen, of a work piece receptacle, work piece feeding mechanism therefor, a 45 shiftable feed roll engaging the platen, and a link controlled by the line-space mechanism to thrust the feed roll out of the path of the work piece.

50 7. The combination with a writing machine including a carriage fed in letter-spacing direction, a revolute platen mounted in the carriage, a line-space lever to turn the platen and to return the carriage toward initial position, and main feed rolls for the 55 platen, of a work piece receptacle, feed mechanism controlled by the carriage on its return toward initial position to extract the work pieces singly from the receptacle and advance them toward the platen, a shiftable auxiliary feed roll engaging the platen and controlled by the line-space mechanism to move out of the path of the work piece, and means to return the auxiliary feed roll to press the work piece against the platen.

60 8. The combination with a writing ma-

chine having a carriage fed in letter-spacing direction, a revolute platen on the carriage, and a line-space lever to turn the platen and return the carriage to initial position, of an envelop receptacle having a discharge slot, 70 ejectors to catch beneath the flap of an envelop to push it through the slot, a vibratory frame carrying the ejectors, a shaft, a motion multiplying arm mounted on said shaft and connected to the frame, a second 75 arm mounted on said shaft, a feed lever having a slot and pin connection with said second arm, the free end of the feed lever lying in the path of the carriage to be operated as the carriage is returned toward 80 initial position, and means to return the ejectors to idle position.

9. The combination with a writing machine having a carriage fed in letter-spacing direction, a revolute platen, and a line-space lever to turn the platen and to return the carriage to initial position, of a work piece receptacle having a discharge orifice, 85 ejectors to thrust the work pieces singly through the orifice, a frame carrying said 90 ejectors, slides on the frame, guides for the slides, and a lever system connected to the frame and controlled by the carriage on its return toward initial position to operate the work piece feeding mechanism. 95

10. The combination with a writing machine having a carriage fed in letter-space direction, a revolute platen, a line-space lever to turn the platen and return the carriage toward initial position, and feed rolls 100 for the platen, of a work piece receptacle supported adjacent the platen, feed mechanism controlled by the return of the carriage to initial position to partially eject a work piece from the receptacle, and auxiliary 105 feed mechanism controlled by the line-space mechanism effective to press the partially ejected work piece against the platen subsequent to the return of the carriage.

11. The combination, with a carriage fed in letter-spacing direction, a revolute platen, a line-space lever to rotate the platen and return the carriage toward initial position, and feed rolls for the platen; of a work-piece supporting and delivering 110 mechanism; an auxiliary feed roll normally engaging said platen; swinging arms supporting the auxiliary feed roll; and a link operative by said lever for swinging said auxiliary feed roll out of the path of the 115 work-piece.

12. The combination with a writing machine having a traveling carriage, a platen rotatably mounted thereon, line-space mechanism to turn the platen, and feed rolls 120 for the platen, of a stationary work piece receptacle, ejecting mechanism to positively extract the work pieces separately from the receptacle and advance them directly to the platen, and an auxiliary feed roll held dis- 125

- engaged from the platen as a work-piece is advanced thereto and adapted to be released against the advanced work-piece.
13. The combination with a writing machine having a traveling carriage, a platen rotatably mounted thereon, line-space mechanism to turn the platen, and feed rolls for the platen, of a stationary work piece receptacle, ejecting mechanism to extract the work pieces separately from the receptacle and advance them to the platen, and auxiliary feed mechanism shiftable out of the path of the advancing work piece, to press the work piece against the platen.
14. The combination with a writing machine having a traveling carriage, a platen rotatably mounted thereon, line-space mechanism to turn the platen, and feed rolls for the platen, of a stationary work piece receptacle, ejecting mechanism to extract the work pieces separately from the receptacle and advance them to the platen, and auxiliary feed mechanism controlled by the line-space mechanism to be shifted out of the path of the advancing work piece, to press the work piece against the platen.
15. The combination with a writing machine having a traveling carriage, a platen rotatably mounted thereon, line-space mechanism to turn the platen, and feed rolls for the platen, of a stationary work piece receptacle, ejecting mechanism dependent upon the return of the carriage toward initial position to extract the work pieces separately from the receptacle and advance them to the platen, and auxiliary feed mechanism controlled by the line-space mechanism to be shifted out of the path of the advancing work piece, to press the work piece against the platen.
16. In a typewriter, the combination, with a traveling carriage; of an envelop receptacle; a reciprocating feeding member movable across the face of the receptacle and having fingers to engage within the flap of the foremost envelop; said receptacle having an opening therein to permit such engagement; and means for operating said member from said carriage.
17. The combination, with a paper carriage arranged to travel in letter-spacing direction and return, and a platen on said carriage; of a stationary work-piece receptacle; and a movable device dependent for its operation upon the return movement of the carriage for automatically transferring a work-piece bodily from said receptacle directly to said platen at a single movement of said device.
18. The combination, with a paper carriage arranged to travel in letter-spacing direction and return, and a platen on said carriage; of a stationary work-piece receptacle, a device movable with relation to said receptacle to forcibly eject a work-piece

therefrom and transfer it bodily to said platen; and means dependent upon the return movement of the carriage for operating said device.

19. The combination, with a paper carriage arranged to travel in letter-spacing direction and return, and a platen on said carriage; of a stationary work-piece receptacle; an ejector movable with relation to said receptacle to directly engage a work-piece and forcibly remove the same from the receptacle and transfer it bodily by a single movement directly to said platen; and means dependent upon a return movement of the carriage for operating said ejector.

20. The combination with a writing machine including a carriage fed in letter-spacing direction, a platen mounted on the carriage, and feed rolls co-acting therewith, of a stationary work-piece receptacle, an auxiliary feed roll, and mechanism operable by the carriage on its return toward initial position to positively feed work pieces singly from the receptacle to a position between the platen and said auxiliary roll.

21. The combination, with a paper carriage arranged to travel in letter-spacing direction and return, and a platen on said carriage; of a stationary work-piece receptacle; mechanism controlled by the return movement of the carriage to positively feed the work-pieces successively and directly to the platen; means to press the work-pieces so fed against said platen; and a spring to return said feeding mechanism to normal position.

22. The combination of a paper carriage; a platen rotatably mounted thereon, line-spacing mechanism; feed rolls associated with the platen; a work-piece receptacle supported independently of the carriage, to relieve the latter of its weight; an ejecting mechanism to feed the work-pieces singly from said receptacle to the platen, said ejecting mechanism including an operating part which lies in the path of the carriage and is adapted to be engaged thereby when said carriage is returned toward initial position; auxiliary feed mechanism associated with said platen and adapted to be thrown to idle position by the line-spacing mechanism as a work-piece is fed to the platen, said auxiliary feed mechanism, upon the release of the line-spacing mechanism, being adapted to press the work-piece against the platen, to feed it to said feed rolls when said platen is rotated; and means to return the various parts to normal position.

23. The combination with a writing machine including a carriage fed in letter-spacing direction, and a platen mounted to rotate thereon, of a stationary receptacle, means for feeding disconnected work-pieces therefrom to the platen, and movable means

for receiving said work-pieces as fed and for pressing them against the platen after said feeding movement and prior to rotation of the platen to further advance the work-pieces.

24. The combination, with a paper carriage arranged to travel in letter-spacing direction and return, and a platen on said carriage; of line-spacing mechanism, including an operating lever therefor operable to return the carriage toward initial position; mechanism operable automatically by said carriage, when the latter reaches such position, to feed a work-sheet to the platen; and a feed roll normally disposed against the platen, but movable by said lever away from said platen at the inception of the line-spacing operation, said roll being returnable at the conclusion of the work-piece feeding operation, to press the fed work-piece against said platen.

25. In a typewriter, the combination of a carriage, a device to feed an envelop and to positively control it while feeding, a bell crank lever connected to said device, and a pivoted arm operatively connected to said lever and carrying a tappet in position to be operated by the carriage.

26. The combination, with a paper carriage arranged to travel in letter-spacing direction and return, and a platen on said carriage; of feeding mechanism operable during the complete return movement of the carriage to deliver a work-piece directly to the platen, said mechanism being inoperative at any return movement of the carriage short of the initial letter-space; and means for pressing against the platen a work-piece so delivered thereto, said means being automatically releasable from said platen at the inception of the aforesaid return movement of the carriage and prior to the operation of the feeding mechanism, but re-engageable with said platen before the return movement of said feeding mechanism has commenced.

27. The combination with a writing machine comprising a rotary platen, of a feed roll, means for holding the feed roll off the platen, work-piece feeding mechanism to carry work-pieces into position between the platen and said roll, and means to return the roll after the work-pieces have been fed to such position.

28. The combination with a writing machine comprising a traveling carriage, a rotary platen thereon, and line-space mechanism, of a receptacle for work-pieces, a feed roll, mechanism to lift said roll from the platen, coördinating mechanism to carry a work-piece from the receptacle into position between the platen and said roll, and means to return the roll after the work-piece has been so positioned.

29. The combination with a writing ma-

chine comprising a rotary platen, of a feed roll bearing against the platen, a receptacle for work pieces, a feeding device to carry a work piece from the receptacle to a position between the platen and said roll, and means to return the roll to operative position prior to the withdrawal of said feeding device.

30. The combination with a typewriting machine comprising a traveling carriage, a platen thereon, line-space mechanism, and a lever to operate said mechanism and return the carriage, of a feed roll bearing against the platen, connections between said lever and said roll for moving the latter from the platen when said lever is operated to rotate the platen and return the carriage, a receptacle for work-pieces, feeding mechanism for the work pieces comprising a frame operated by the return movement of the carriage to carry a work-piece into position between the platen and said feed roll, means to return the feed roll when the line-space lever is released, and means to withdraw said frame when a forward movement is imparted to the carriage.

31. The combination with a writing machine including a carriage arranged to travel in letter spacing direction and return, and a platen on the carriage, of a stationary work-piece receptacle, a vibratory frame, ejectors on said frame to positively extract the work-pieces singly from the receptacle and deliver them to the carriage, mechanism controlled by the return movement of the carriage to initial position to operate the frame, and means operable independently of the travel of the carriage to press the work-pieces against the platen.

32. The combination with a carriage arranged to travel in letter-spacing direction and return, a platen on said carriage, and line-space means for said platen, of a work-piece receptacle supported without movement directly over the carriage and extending close to the platen, means operating with the return movement of the carriage to feed a work-piece by a single movement from said receptacle down to the introductory side of the platen, and means operable to receive and hold to the platen said work-piece as fed.

33. The combination, with a carriage arranged to travel in letter-spacing direction and return, and a platen on said carriage; of a work-piece receptacle having a discharge opening directly over the introductory side of the platen; and means controlled by the movement of the carriage for shifting a work-piece bodily, at a single motion of said means, through the opening in said receptacle to the introductory surface portion of the platen, and in contacting relation with the same.

34. The combination, with a carriage

arranged to travel in letter-spacing direction and return, and a platen on said carriage; of a work-piece receptacle having a discharge opening directly over the introductory side of the platen; and means operable consequent upon the return movement of the carriage for shifting a work-piece bodily, at a single motion of said means, through the opening in said receptacle to the introductory surface portion of the platen, and in contacting relation with the same.

35. The combination, with a carriage arranged to travel in letter-spacing direction and return, a platen on said carriage, and line-space means for said platen; of a work-piece receptacle having a discharge opening directly over the introductory side of the platen; means for feeding a work-piece in a single motion through the opening in said receptacle to the platen; and movable means controlled by said line-space means to receive the work-piece as fed, and to hold it against the platen.

36. The combination, with a platen, an introductory feed roll running on the back thereof, and a line-space lever; of a rock shaft carrying said roll and having a cranked operating end or wrist; and a horizontally-disposed link connected to said wrist and having its free end lying in the path of said lever to be shifted endwise by the latter when line-spacing the platen, whereby said roll is caused to be removed from contact with the platen at such time.

37. The combination of a carriage fed in letter-spacing direction; a revoluble platen; feed rolls associated with the platen; line-space mechanism including a slide for rotating said platen and provided with a lip, and a lever for operating said slide and for returning the carriage toward initial position; a work-piece supplying mechanism; an auxiliary feed roll normally engaging the platen; swinging arms supporting the auxiliary feed roll; and a link engageable by the lip on said slide, when the latter is operated by the line-space lever, to swing said auxiliary feed roll out of the path of the work-piece.

38. The combination, with a platen and an introductory feed roll running on the back thereof; of a line-space mechanism including a slide for rotating said platen and provided with a lip, and a lever for operating said slide; a rocking frame; a shaft mounted in said frame and carrying said roll, said shaft having a crank-operated end or wrist; and a horizontally-disposed link connected to said wrist and having its free end disposed behind said lip, to be shifted endwise by the slide when the latter is operated by said lever, whereby said frame is rocked to remove said roll from contact with the platen at such time.
